TIRE

Robert F. Busch, St. Clair Shores, Mich., assignor to
United States Rubber Company, New York, N.Y., a
corporation of New Jersey

Filed Nov. 12, 1963, Ser. No. 77,380

Term of patent 14 years

(Cl. D90—20)

Fig. 1

FIG. 1 is a perspective view of a tire embodying my new design, it being understood that the full line portion is repeated throughout the circumference of the tire, shown by means of broken lines;

FIG. 2 is an enlarged fragmentary elevational view of the full line sidewall portion shown in FIG. 1;

FIG. 3 is a further enlarged fragmentary plan view of the full line tread portion shown in FIG. 1;

FIG. 4 is a sectional view taken substantially on the plane indicated by line IV-IV of FIG. 3, but also on the same scale as FIG. 2;

FIG. 5 is a detailed sectional view taken substantially on the plane indicated by line V-V of FIG. 2; and

FIG. 6 is another detailed sectional view taken substantially on the plane indicated by line VI-VI of FIG. 2.

The dominant features of my design reside in those portions shown in full lines in the drawing.

I claim:

The ornamental design for a tire, substantially as shown and described.
